CONSTRUCTION SYSTEM

Harold P. Ford, Seattle, Wash.

Application September 21, 1936, Serial No. 101,739

7 Claims. (Cl. 189—1)

My invention relates to a system of building construction, and the general object of my invention is to provide a simple, fire resistant or fireproof, strong and secure, attractive, permanent and low-cost system of construction, more especially for homes and other buildings in which load requirements are light; having lightweight open web steel framework with units standardized to a maximum extent, and yet which permits any type of architectural design; having lightweight surfacings; having efficient heat insulation; adaptable to easy installation of various items of modern mechanical and electrical equipment; and conforming to standard engineering principles.

It is my purpose to use standard steel shapes, widely available at the lowest cost, and to use simple machinery and simple plant, in the fabrication and erection of structures embodying my invention.

The time will probably come, when certain other metals or alloys will be largely used instead of steel in the form in which it is commonly known. Therefore, wherever the term steel is used herein, the same shall be held to include other metals and their various alloys.

The above mentioned general objects of my invention, together with others inherent in the same, are attained in the manner illustrated in the following drawings, the same being preferred exemplary forms of my invention, throughout which drawings like reference numerals indicate like parts:

Fig. 1 is a fragmentary side elevation of an open web beam connected to an open web column.

Fig. 2 consists of a typical vertical section thru the beam, taken at 2—2, in Fig. 1.

Fig. 3 consists of a typical horizontal section, taken at 3—3 in Fig. 1, thru an open web column.

Fig. 4 is a typical vertical section thru a single beam or joist, showing a transverse stiffening and supporting member disposed thru the open web, together with timber members disposed along the upper sides of the beam for the support of a sub-floor or sub-roof, all web members being omitted.

Fig. 5 consists of a fragmentary vertical elevation of an open web steel column shown connected to an open web steel beam, together with a fragmentary vertical section thru a floor or roof, and thru a ceiling.

Fig. 6 consists of a fragmentary vertical section, taken at 6—6 in Fig. 5, showing fire-resistant floor or roof construction, and ceiling construction.

Fig. 7 is a typical horizontal section, taken at 7—7 in Fig. 5, thru an open web column, together with a timber member for attachment of wall surfacings.

Fig. 8 is a fragmentary horizontal section 5 showing fire-resistant wall construction.

Fig. 9 is a fragmentary side elevation of a roof truss.

Fig. 10 is a typical section, taken at 10—10 in Fig. 9, thru the roof truss, showing a transverse 10 stiffening and supporting member, together with timber members along the upper sides of the truss for attachment of a sub-roof.

Fig. 11 is a fragmentary horizontal section 15 showing a fire-proof wall construction, and showing the wall bearing and connecting girders, on inner wall faces, at floor and roof levels.

Fig. 12 is a typical vertical section, taken at 12—12 in Fig. 11, thru a long-wall connecting 20 and bearing girder which is perpendicular to the joists.

Fig. 13 is a typical fragmentary outside elevation of a long-wall bearing and connecting girder.

Fig. 14 is a typical vertical section, taken at 14—14 in Fig. 11, thru a short-wall bearing and 25 connecting girder, which is parallel to the joists.

Fig. 15 is a typical fragmentary outside elevation of a short-wall bearing and connecting girder.

Fig. 16 is a fragmentary vertical section thru a 30 fireproof floor, or roof, and ceiling, construction.

Referring first to Fig. 1, I show a fragmentary side elevation of an open web beam having a top chord 1, a bottom chord 2 and web members 3 connected at points 4, as by rivets, or by spot 35 welds with thin metal sections, to form openings 5 in the web of the beam; together with an open web column having an inner flange 6 and an outer flange 7, connected by web plates 8 to form openings 9 in the web of the column; together with a sectional view of an upper chord 10 and a lower chord 11 of a wall bearing and connecting 40 girder. The inner flange 6 of the column supports the upper chord 10 and the lower chord 11 of the wall bearing and connecting girder, which 45 in turn supports the open web beam at its top chord 1 and bottom chord 2.

In Fig. 2 I show a vertical section thru a beam, wherein top chord 1 consists of double bars of suitable section, and bottom chord 2 consists of 50 similar double bars.

In Figs. 1 and 2 I show an open web steel beam in which vertical members 12, preferably angles, are situated in pairs on opposite sides of the beam, with pairs spaced apart along the beam, 55

and connecting outer edges of the top flange with outer edges of the bottom flange, as at points 13, and preferably by welding.

- 5 In Figs. 1 and 2 I show open web steel beams in which the web bars or trussing members 3 consist of a dished or troughed section in the center length or main length of the web bar, with flattened ends to facilitate connection to the top and bottom chords. The web bars 3 may 10 consist of a channel or angle section with its ends flattened; but are preferably flat bars dished or troughed to a U or V mid-section, to increase the stiffness of the member. The flat bar, from which the member is pressed or formed, may vary 15 in width and/or in thickness, to give web bars 3 which vary in cross sectional area and hence in stiffness, in different parts of the beam, to conform to the varying shear and diagonal web stresses.
- 20 In Fig. 3 I show in horizontal cross section an open web steel column consisting of a main bearing angle having a wide leg or flange 6 on its inner face, connected in spaced relation by spaced connection plates 8 to a stiffening angle having 25 a narrow outer face or flange 7, to form preferably a channel section.

30 In Figs. 1 and 5 I show in elevation the open web steel column construction, shown in cross section in Fig. 3, and consisting of two angles connected in a spaced apart manner to form preferably a channel section, having the wide flange 6 on the inner wall face, and the narrow flange 7 on the outer wall face, with the two angles connected in spaced relation by the spaced 35 plates 8, with alternate plates disposed on opposite sides of open column web. Connection plates 8 are preferably provided with holes, for attachment purposes.

40 In Figs. 4, 5 and 6 I show an open web steel floor and roof construction in which paired vertical members 12 are spaced along the beam, together with spaced horizontal stiffening and bearing members 18, preferably channels, connected at points 19 to both of paired vertical 45 members 12, with members 18 perpendicular to web plane 20 of the open web beams. This construction permits rigid side stiffening of the series of beams; prevents beams from twisting or canting; and affords excellent bearing means for ceiling construction.

50 In Figs. 4, 5 and 6 I also show timber members 21 connected along upper sides of the beam to spaced paired members 12, at points 22, preferably by bolts, thus to form, together with the open web beam, a T-section. The timber members 21 are disposed with their tops approximately at the same level as the tops of beam flanges 1. This construction provides added 55 stiffening for the top chord, and provides nailing means for securing the wood sub-roof or sub-floor 23, the same being preferably full thickness 2-inch planking, thus permitting a wide center to center spacing of beams. In Figs. 4, 5 and 6 the web members 3 are indicated by center lines.

60 In Figs. 5 and 6 I show floor and roof surfacing secured to the wood sub-floor or sub-roof 23. The surfacing shall preferably consist of a watertight metal membrane plasterbase 24 together with surface 25 of adhering weatherproof plaster 65 or stucco; or surfacing may consist of open metal mesh 26 together with plastered surface 25.

70 In Figs. 5 and 6 I also show a ceiling construction in which the transverse bearer bars 18 support spaced bars 27, parallel to the beams, with 75 the bottoms of the bars 27 in the same plane as

the bottom face or flange 2 of the beam, forming a plane for the support of metal lath 28 and plastered ceiling 29. Loose porous mineral fill 30 may be placed on top of the metal lath 28, to insulate the ceiling against the transmission of heat or sound.

75 In Figs. 7 and 8 I show a type of column and outer wall construction consisting of the open web steel columns having a channel section with the wide inner flange 6, and the narrow outer flange 7, together with a timber nailing member 31 secured to the open web of each of the columns, with the inner and outer faces of the timber member 31 in the same planes as the inner and outer column flanges, together with a 10 wood sub-wall 34, preferably of full thickness 2-inch planks, secured over the outer wall face of the columns, and with a metal membrane plaster-base 24 secured to the outer sub-wall 34, and with a surfacing of weatherproof plaster or stucco 15 over the plasterbase 24. Spaced non-load bearing vertical furring members 32, preferably bar channels, have their inner faces in the same plane as the inner column faces or the flanges 6, thus forming a plane for the support of the metal lath 28 and the plastered surface 29. Loose 20 porous insulating fill may be used in the wall space between columns; or sheet insulating material 33 may be secured to the inner face of the outer sub-wall 34. This results in strong, durable, 25 warm outer wall construction which is fire-resistant, and is of low cost.

30 In Figs. 9 and 10 I show a truss construction wherein diagonals 3 consist of pipe or tubing, with ends flattened for connection to the top chord 1 and the bottom chord 2, together with paired vertical members 12, bearing and stiffening members 18, timber nailing members 21, wood sub-roof 23, metal membrane plasterbase 24, and weatherproof plastered surface 25.

35 In Fig. 11 I show in horizontal section a type of fireproof outer wall construction, consisting of the open web columns having inner flanges 6 and outer flanges 7, together with porous, or thin-wall hollow, fireproof block construction 35 in the 40 outer wall space between columns; and with metal reinforcing rods 36 disposed in the joints of the block construction and extending thru the open webs of the columns; together with the spaced non-load bearing vertical furring members 32 in the inner wall space between the columns; and with the metal membrane plaster-base 24 and plastered surface 25 over the outer 45 faces of the columns and the block construction 35.

50 In Figs. 5, 11, 12, and 13 I show a connecting and supporting girder for use at the floor and/or roof lines, in the long wall or that wall perpendicular to the web plane 20 of the beams; with the top chord 10 in the angle between the plane of the bottom surfaces of beam top chords 1, and the plane of the inner flanges 6 of the columns; with the bottom chord 11 in the angle between the plane of the bottom surfaces of beam bottom chords 2 and the plane of the inner flanges 6 of the columns; together with vertical members 37 connecting the outer faces of the chords 10 and 11, and provided with holes 38 for the attachment of the vertical non-load bearing furring members 32; together with diagonal or trussing members 39 connecting the chords 10 and 11; and with means shown at 40 for connecting chord members 10 and 11 to the inner column flanges 6. Columns and vertical members 32 are 55 60 65 70 75 80 85 90 95 100 105 110 115 120 125 130 135 140 145 150 155 160 165 170 175 180 185 190 195 200 205 210 215 220 225 230 235 240 245 250 255 260 265 shown dotted in Fig. 13. In Fig. 12 one end of the beam is shown dotted.

In Figs. 11, 14 and 15 I show a connecting and supporting girder for use at the floor and/or roof lines, in the short wall, or that wall parallel to the length of the beams, with the top face of top chord 41 in the same plane as the top faces of beam top chords 1, and with the bottom face of bottom chord 42 in same plane as the bottom faces of beam bottom chords 2, together with vertical members 37 connecting the outer faces of the chords 41 and 42, and with holes 38 for the attachment of the vertical furring members 32, shown in dotted outline in Fig. 15. The trussing members 39 connect chords 41 and 42. Means, as shown at 40, are provided for connecting chord members 41 and 42 to the inner column flanges 6, shown in dotted outline in Fig. 15. In Fig. 14 I show a vertical section of a short wall bearing and connecting girder, with vertical members 12, preferably angles, connecting the inner edges of the top and bottom chords, and with a wood nailing member 21 attached to members 12, parallel to the length of the girder, and with the top of member 21 lying in the same plane as does top chord 41.

In the herein described construction system, columns and joists are intended to be standardized for economical production. A wide spacing of each is possible. Spacing of the columns may be independent of the spacing of joists through the use of connecting and supporting girders. Lightweight steel framework may be quickly erected on foundations, and exterior watertight surfacing quickly applied over the framework, after which all other construction may be finished, without interference due to adverse weather conditions.

Obviously, changes may be made in the form, dimensions and arrangement of the parts of my invention, without departing from the principle thereof; the above setting forth only a preferred embodiment.

I claim:

1. In a structure of the class described, the combination with vertical walls of a plurality of open web metal joists supported by the walls, a plurality of spaced cross members disposed transversely of and thru the open webs of the joists and rigidly affixed thereto, and a plurality of spaced ceiling bars disposed transversely the cross members and supported therefrom.

2. In a structure of the class described, the

combination with columns of open web metal wall girders attached thereto at floor levels, non-load bearing vertically extending wall furring members attached to the wall girders, and open web metal joists supported by the wall girders. 5

3. A construction system comprising a plurality of spaced open web metal columns, and open web metal wall girders attached thereto at floor levels and adapted to support floor joists, and non-load bearing vertically extending wall 10 furring members attached to the wall girders.

4. In a system of construction, a plurality of spaced columns, an open web metal wall girder attached thereto at floor level and consisting of a top chord, a bottom chord, and outstanding 15 vertical members disposed between and affixed to the top chord and the bottom chord, and non-load bearing wall furring members secured to the outstanding vertical members.

5. In a system of construction, a plurality of spaced columns, an open web metal wall girder attached thereto at floor level and consisting of a top chord, a bottom chord, outstanding vertical members disposed between and affixed to the top chord and the bottom chord and adapted to receive non-load bearing vertical wall furring members, and trussing members disposed between and affixed to the top chord and the bottom chord. 25

6. In a system of construction, spaced open 30 web metal wall columns, open web metal wall girders disposed at floor levels and affixed to the wall columns and consisting each of a top chord, a bottom chord, outstanding vertical members disposed between and affixed to the chords and 35 adapted to receive non-load bearing vertical wall furring members, and open web metal joists disposed transversely the wall girders and affixed thereto.

7. In a system of construction, spaced open web 40 metal wall columns; open web metal wall girders disposed at floor levels and affixed to the wall columns and consisting each of a top chord, a bottom chord and outstanding vertical members connecting the chords and adapted to receive vertical members; spaced open web metal joists disposed transversely the wall girders and supported thereby; spaced cross members disposed transversely of and through the open webs of the joists and rigidly affixed thereto; and a 45 plurality of spaced ceiling bars disposed transversely the cross members and supported thereby. 50

HAROLD P. FORD.
